UNITED STATES PATENT OFFICE.

FRANK B. WILDMAN AND GEORGE L. BALLARD, OF NORRISTOWN, PENNSYLVANIA,
ASSIGNORS TO WILDMAN MFG. CO., A CORPORATION OF PENNSYLVANIA.

CIRCULAR-KNITTING MACHINE

1,106,764.

Specification of Letters Patent. Patented Aug. 11, 1914.

Application filed March 7, 1913. Serial No. 752,795.

To all whom it may concern:

Be it known that we, FRANK B. WILDMAN and GEORGE L. BALLARD, a citizen of the United States and a subject of the King of Great Britain, respectively, residing at Norristown, Pennsylvania, have invented certain new and useful Improvements in Circular-Knitting Machines, of which the following is a specification.

Our invention relates to knitting machines of the circular type for making two and two rib fabric, it having preferably a racking dial to alter the relation of the needles from 1 and 1 to 2 and 2, or the reverse, and it concerns particularly means for making a loose course in the two and two fabric.

In the accompanying drawings, Figure 1 is a plan view of a circular knitting machine embodying our invention, this view being partly broken away and with parts omitted; Fig. 2 is a side view of part of the knitting head, parts being omitted; Fig. 3 is a diagrammatic view showing the relation of the stitch cams; Fig. 4 is a diagram of the two and two fabric. Fig. 5 is a bottom plan view of the dial cap.

In these drawings, 1 is the fixed cylinder, 2 the fixed dial, 3 the rotary cylinder cam box, 4 the rotary dial cap carrying the dial cams. These cams comprise, as shown in dotted lines, Fig. 1, the stitch cam 5 pivoted at 6 and the advancing cam 7. The stitch cam of the cylinder is marked 8, being shown in dotted lines in Fig. 2, and diagrammatically in Fig. 3. The two and two arrangement of the needles is indicated in Fig. 2, the dots *x* indicating the ends of the dial needles while the lines *y* indicate the cylinder needles. In the formation of the stitches of a two and two fabric, the casting off of the loops takes place in the order indicated in Figs. 3 and 4 by the letters *a*, *b*, *c* and *d*, the letters *a*, *b*, indicating the pair of cylinder needles or cylinder stitches, and *c*, *d*, indicating the pair of dial needles or dial stitches. It is essential that this sequence be preserved in order that the thread will render properly in drawing the loops. If this order of drawing the loops is disturbed, the yarn will be strained or broken. For instance, if the cylinder stitch cam alone were adjusted, the relative times of drawing the loops would be altered, and

for instance a loop would be drawn on a dial needle at the same time that it is drawn on a cylinder needle. We therefore provide means by which the time of drawing the loops or the time at which the hooks of the cylinder and dial needles reach the sinker line of the cylinder and dial will be preserved in this two and two fabric.

For adjusting the cylinder cam we employ mechanism similar to that heretofore used in the Wildman type of circular machine, in which a plate 9 is fixed to the post 10 of the cylinder stitch cam 8, said plate having an inclined top to be engaged by an adjustable pin or screw 11 carried by a swinging arm 12 on a rock shaft 13 journaled in the cam box, said rock shaft being turned one way by its tappet arm 14 striking a pattern controlled roller 15, and turned the other way by a return arm 16 on a rock shaft 17 geared at 18 to the rock shaft 13, it being understood that the pattern-controlled roller is mounted on a pin or rod 19 passing down through the fixed bed of the machine, suitable pattern mechanism, well known in the Wildman type of machine, elevating or lowering this roller into line with the tappet arms at the proper times. When this swinging arm 12 moves inwardly toward the center of the machine, it causes its pin to ride on the incline of the plate 9 and thus presses the cylinder stitch cam downwardly.

The diagram, Fig. 3, illustrates by the dotted line *z* the position of this cam when moved down. *w* indicates the sinker line of the cylinder, and *w'* the sinker line of the dial; *e*, *f*, represent respectively the knitting off points of the cylinder and dial stitch cams. It will now be observed that if the cylinder cam alone is adjusted the cylinder needle will reach the sinker line and begin to draw stitches earlier in relation to the revolution of the machine, and they will more nearly coincide with the times of drawing the loops on the dial, resulting in straining and breaking the thread. In order to avoid such action, we adjust the dial stitch cam at the same time that the cylinder stitch cam is adjusted, and in a degree to maintain the times of casting off. While this adjustment may be variously effected, the invention, in its best form, consists in utilizing the movement of the swinging arm 12 for

operating the stitch cam of the dial, and we therefore place an arm or projection 20 on the swinging arm 12, which strikes the stitch cam 5 passing for this purpose below the 5 dial cap. Therefore, as the arm 12 swings toward the center of the dial, the arm 20 will strike the stitch cam 5 and move it inwardly at the same time and to the same extent that the cylinder stitch cam is moved, so that the 10 relative times of drawing loops in respect to the two and two arrangement of the needles will be preserved in making this loose course as in making the regular two and two rib. By this invention not only are long loops 15 formed on both the cylinder and dial for the loose course, but the thread is not strained, and furthermore the loose course will be clearly visible on both sides of the fabric.

The racking of the dial may be accomplished in various ways. We have shown an arm 21 for this purpose which is connected with the dial through a dogless arrangement, like that disclosed in Letters Patent of the United States granted to G. L. Ballard, 25 December 20, 1911, #1,012,966, this arm corresponding to the arm 14 of said patent, but in the present invention it is operated automatically by an arm 22 on the vertical rock shaft 23, this rock shaft being operated 30 through suitable connections to a pattern mechanism.

The pattern wheel is shown generally at 24, this being operated by any suitable pattern mechanism common in the Wildman 35 type of machines. It has pattern blocks 25 for operating a lever 26 which raises and lowers the pattern disk 15, said lever being pivoted to the frame at 27, and the pattern wheel also has pattern blocks 28 for operating 40 connections 29, 30, shown generally in dotted lines in Fig. 1 for operating the vertical rock shaft 23, from which it will be seen that the control of the shogging and the operation of the loose course attachment 45 takes place automatically and in its best form from the same pattern wheel.

When the dial is shogged it is revolved against the direction of motion of the cams. Consequently, when it is desired to return 50 the dial to its original position, it is merely released; upon which, the action of the cams through the needle butts against the dial turns the latter back to the original position.

The dial stitch cam is returned to normal 55 position by the coil spring bearing thereon, as indicated in Fig. 1. The cylinder stitch cam is returned by the usual coil spring shown in Fig. 2 pressing up against the under side of the cam member 9.

We claim as our invention:—

1. In combination with a cylinder and dial having their needles arranged in two and two relation, a cylinder stitch cam, a dial stitch cam, said cams being adjustable substantially in unison for making a loose 65 course, means for adjusting both of said cams when the loose course is to be made, and means for shogging the dial, substantially as described.

2. In combination in a knitting machine, 70 a cylinder and dial, stitch cams therefor, means for shogging the dial to a two and two relation, means for shifting the stitch cams in unison for making loose courses in the two and two fabric, including a swinging 75 arm and a projection thereon to contact with and to be retracted away from the dial cam as the arm swings to and from the dial, pattern controlled means for operating the shogging means and the stitch cam shifting 80 means, and means for returning the stitch cams to normal position, substantially as described.

3. In combination with a fixed cylinder and dial, a stitch cam for the cylinder and a 85 stitch cam for the dial, a post connected with the cylinder stitch cam having a cam plate on its upper end, a swinging arm carried by the rotary cam box of the cylinder having a portion to engage the cam plate for depressing 90 the cylinder stitch cam, said arm having a projection to contact with and operate the dial stitch cam when said arm swings toward the axis of the head, and to be retracted away from the dial cam when the arm 95 swings back, tappet arms for operating the swinging arm, and a pattern controlled member for operating the tappet arms, substantially as described.

4. In combination with a cylinder and 100 dial, stitch cams for the cylinder and dial, a member having a back and forth movement toward and from the dial, a post connected with the cylinder stitch cam and operated by said member, and a pin mounted on said 105 member and adjustable longitudinally thereon to alter the position of its end in relation to the dial stitch cam, said end contacting with the dial stitch cam to adjust the same, substantially as described.

In testimony whereof, we affix our signatures in presence of two witnesses.

FRANK B. WILDMAN.
GEORGE L. BALLARD.
